BY

W. Randolph, Jr. ATTORNEY.

UNITED STATES PATENT OFFICE.

CHARLES W. MARKS, OF TRACY, MINNESOTA.

DESIGN FOR A PENNANT.

58,393.

Specification for Design.

Patented July 12, 1921.

Application filed June 16, 1920. Serial No. 389,493. Term of patent 7 years.

To all whom it may concern:

Be it known that I, CHARLES W. MARKS, a citizen of the United States, residing at Tracy, in the county of Lyon and State of Minnesota, have invented a new, original, and ornamental Design for a Pennant, of which the following is a specification, reference being had to the accompanying drawing, forming part thereof.

The figure is a plan view of my new design for a pennant.

I claim:

The ornamental design for a pennant as shown.

CHARLES W. MARKS.

Witnesses:

ROY F. NACUN,
ISABEL REGNIER.
